POLLENIZER

Ray H. Clark, Star City, Ind.

Application June 20, 1940, Serial No. 341,566

6 Claims. (Cl. 47—1)

This invention relates to a machine or device for the fertilization of plants, such as clover by providing means for removing the pollen from the blossoms for releasing the stamens therefrom for causing the distribution of the pollen to the blossoms of other plants to insure fertilization thereof.

More particularly, it is aimed to provide a device of the character heretofore described of simple construction, capable of being easily and efficiently operated to fertilize clover, in a relatively large area very quickly and efficiently; and provided with means for adjusting the elevation of the pollinating element to adjust the element to stands of clover of different heights.

It is a further aim of the invention to provide a pollinator employing an elongated rotary brush for accomplishing the pollinating and fertilization of a plant, which is especially adapted for use on clover, the blossoms of which stand substantially upright and have relatively deep bowls, so that it is necessary to provide a device, such as a revolving brush, that will enter the bowls for releasing the pollen from the bloom.

Other objects and advantages of the invention will hereinafter become more fully apparent from the following description of the drawings, which illustrate a preferred embodiment thereof, and wherein:

Figure 1 is a top plan of the machine,

Figure 2 is an enlarged vertical sectional view taken substantially along the plane of the line 2—2 of Figure 1,

Figure 3 is a longitudinal vertical sectional view, on an enlarged scale, taken substantially along the plane of the line 3—3 of Figure 1,

Figure 4 is a transverse vertical sectional view taken substantially along the plane of the line 4—4 of Figure 3, and

Figures 5 and 6 are transverse vertical sectional views taken substantially along the planes of the lines 5—5 and 6—6, respectively, of Figure 1.

Referring more particularly to the drawings, wherein like reference characters designate like or corresponding parts throughout the different views, 10 designates generally a vehicle including a pair of ground wheels 11 which are keyed to the ends of an axle 12. A main frame 13, of the vehicle 10, is provided at its sides and intermediate of its forward and rear ends with bearings 14 in which are journaled the axle 12 for supporting the frame 13 between the wheels 11 and beneath the axle 12. The bearings 14 are provided with upwardly projecting lugs 15 having inwardly projecting pins 16 for pivotally mount-

ing the rear end of a secondary frame 17, which is disposed above the forward end of the frame 13 and which is adapted to be supported in substantially a horizontal position by means of a horse, not shown, connected to the shafts 18. These parts of the vehicle 10 correspond substantially to the conventional construction of a hay tedder machine, and are illustrated and described merely to illustrate the application of the pollinating attachment, which will hereinafter be described.

Referring particularly to Figure 2, an arcuately shaped rack 19 is secured to the frame 17 and pivotally mounts a lever 20 having a latch element 21 for engaging the notches of the rack 19 for holding the lever 20 in adjusted positions relatively to the rack. An arm 22 is formed integral with the pivotally connected end of the lever 20 and projects rearwardly therefrom substantially at a right angle to the lever. A link 23 is pivotally connected at one end to an ear 24 which is secured to the forward end of the frame 13, and is provided adjacent its opposite end with a series of spaced openings 25 adapted to be selectively engaged by a removable fastening carried by the free end of the arm 22, designated 26 for adjustably and pivotally connecting the upper end of the bar 23 to the free end of the arm 22. A pair of corresponding arms 27 are secured to the rear end of the frame 13, at the sides thereof, and extend rearwardly from the frame and outwardly relatively to each other so that the free ends of the arms 27 will be off-set outwardly relatively to their secured ends, as best seen in Figure 1. Journal blocks 28, formed of detachable sections 29 are mounted on the free ends of the arms 27 and secured thereto by the nut and bolt fastenings 30, which in addition connect the sections 29. The upper sections 29 of the blocks 28 are provided with lubricating ports 31. An arm 32 is secured to and projects rearwardly from the frame 13, between and substantially intermediate of the arms 27, and is provided at its free end with a bearing block 33 which is detachably mounted thereon by means of nut and bolt fastenings 30. The bearing block 33 is also provided with a lubricating port 31.

A shaft 34, as best seen in Figure 3, includes a rod 35, the ends of which are disposed in the adjacent ends of a pair of pipes or tubes 36. The rod 35 is connected to the tubes 36 by means of wedge shaped pins 37 which extend through alined openings 38 in the rod and tubes and which position the tubes 36 with their adjacent ends in spaced apart relationship. Each of the

journals 28 forms a bearing for one of the pipes 36 and the journal block 33 forms a bearing for the exposed, intermediate portion of the rod 35.

A shaft 39 is journaled in the frame 13 behind and substantially parallel to the axle 12 and is provided, adjacent one end thereof, with a pinion 40 of relatively small diameter which meshes with a relatively large internal gear 41 which is keyed to the axle 12. A relatively large sprocket wheel 42 is keyed to the shaft 39 and a smaller sprocket wheel 43 is keyed to the exposed, intermediate portion of the rod 35. A chain 44 is trained over the sprocket wheels 42 and 43 to revolve the shaft 34 when the wheels 11 are turned, by movement of the vehicle 10, to revolve the axle 12. A roller 45 is connected to the frame 13 by means of a resilient arm 46 and bears against the chain 44 for tensioning the chain.

The journal blocks 28 and 33 and the sprocket wheel 43 are disposed between a plurality of elongated brushes 47, which are circular in cross section and which are detachably mounted on the tubes 36 of the shaft 34. Each of the brushes 47 includes a pair of corresponding sections 48 having head portions 49 which are substantially semi-circular in cross section. The head portions 49 are provided with substantially semi-circular grooves 50 in their flat faces. The head portions 49 are provided with outwardly projecting bristles 51 which are preferably arranged in tufts and secured in the outer sides of the head portions 49. The pairs of brush sections 48 of each of the brushes 47 are mounted on the tubes 36 with their flat faces substantially in abutting engagement and with the grooves 50 receiving and engaging tubes 36. The sections 48 of each of the brushes 47 are clamped to the tubes 36 by means of one or more clamping rings 52 to thereby detachably mount the brushes 47 on the shaft 34.

From the foregoing it will be seen that when the vehicle 10 is moved through a field of clover, for example, the ground wheels 11 being revolved will turn the axle 12 in a clockwise direction, as seen in Figure 2, to rotate the internal gear 41 in a clockwise direction to thereby turn the pinion 40, shaft 39, sprockets 42 and 43, chain 44 and shaft 34 in a clockwise direction. The relative sizes of the pinion 40 and gear 41 and sprocket 43 and sprocket 42 will cause the brushes 47 to be revolved at a greater speed than the axle 12 so that the brushes will engage the pollen in the clover blossoms, not shown, for removing the pollen and distributing it to other clover plants. The lever 20 can be swung rearwardly for raising the brushes 47 or forwardly for lowering the brushes for adjusting them to clover and other plants of different heights and the brushes will be held in adjusted position by the latch element 21 engaging the teeth of the rack 19. For more extreme adjustments, the rod or bar 23 may be adjusted relatively to the arm 22 by means of the series of openings 25, any one of which is adapted to be engaged by the fastening 26. As seen in Figure 1, the brushes 47 extend substantially beyond the sides of the vehicle 10 so that a considerable area of a field may be pollinated each time that the machine moves across the field.

Various modifications and changes are contemplated and may obviously be resorted to, as only a preferred embodiment of the invention has been disclosed.

I claim as my invention:

1. A pollinizer comprising a two wheeled vehicle including a main frame supported by and pivotally mounted relatively to the wheels of the vehicle, means for rocking said frame for raising and lowering the rear end thereof, arms secured to and projecting rearwardly from said frame and provided with bearings at their free ends, a shaft journaled in said bearings, circular brushes carried by said shaft, and means for driving said shaft from the ground wheels of the vehicle for revolving the brushes.

2. A pollinizer comprising a two wheeled vehicle including a main frame supported by and pivotally mounted between and relatively to the wheels, intermediate of its forward and rear ends, arms secured to and projecting rearwardly from the main frame, bearings mounted on the free ends of said arms, a shaft journaled in said bearings, a plurality of circular brushes detachably secured to said shaft, a shaft journaled in the main frame of the tedder and having a pinion keyed thereto, a gear driven by said wheels, said gear being in mesh with the pinion for rotating said last mentioned shaft, sprockets keyed to said shafts, and a chain connecting said sprockets for revolving the circular brushes when the wheels are in motion.

3. A device as in claim 2, said vehicle having lever means for raising and lowering the rear end of said main frame for raising and lowering the brushes.

4. A pollinizer comprising a vehicle including a main frame hung from the axle of a pair of ground wheels and pivotally mounted relatively thereto, said vehicle including a secondary frame disposed above the forward end of the main frame and provided with a lever pivotally mounted thereon and provided with an angularly disposed arm, latch means for retaining said lever and arm in adjusted positions, said secondary frame being pivotally connected to the main frame above the axle, a link pivotally connected to the forward end of the main frame and pivotally and adjustably connected to the free end of said arm for angularly adjusting the main frame relatively to the secondary frame by movement of the lever; arms fixed to and projecting rearwardly from said main frame, bearings carried by the free ends of said last mentioned arms, a shaft journaled in said bearings, circular brushes detachably secured to said shaft and means for connecting said shaft to the ground wheels of the vehicle for revolving the circular brushes when the wheels are revolved.

5. A device as in claim 4, said shaft including a rod, tubes detachably connected at their adjacent ends to the ends of said rod, said circular brushes each including a pair of substantially semi-circular brush heads having outwardly projecting bristles, said brush heads having arcuately shaped grooves for engaging said shaft, and clamping rings for securing the brush heads, of each of said pairs of brushes, to the shaft.

6. A device as in claim 4 comprising a relatively large gear keyed to the axle and rotated by the movement of a ground wheel thereof, a shaft journaled in said main frame and provided with a pinion in mesh with said gear, said last mentioned shaft having a relatively large sprocket wheel, a small sprocket wheel keyed to said first mentioned shaft, and a chain connecting said sprocket wheels for revolving the circular brushes.

RAY H. CLARK.
